CAR TRUCK

Robert B. Cottrell, Chicago, Ill., assignor to
 American Steel Foundries, Chicago, Ill., a corporation of New Jersey

Application June 7, 1940, Serial No. 339,302

28 Claims. (Cl. 105—206)

My invention relates to a railway car truck and more particularly to a novel form of four wheel railway truck comprising cast steel side frames of truss form and a connecting bolster.

An object of my invention is to design such a four wheel truck suitable for present day high speed requirements and capable of accommodating spring groups in each side frame at opposite sides of each journal box, thereby reducing to a minimum the unsprung weight of the truck.

My novel side frame comprehends a truss form with some slight reverse camber in the compression member, said compression member merging at its ends with the diagonal portions of the tension member to form pedestal portions at the ends of the frame with jaws for the reception of associated journal boxes.

My novel form of truss side frame utilizes a tension and compression member with spaced columns defining a bolster opening and other struts spaced from said columns defining a plurality of window openings at each side of the frame outwardly of said columns.

In my novel arrangement the tension member below the bolster opening is of box section and the central portion of the tension member is joined with the pedestal portion of the frame by a horizontal strut extending therebetween, said strut merging at its outer end with one of the walls defining the spring pocket at the inner side of the pedestal jaw. The spring pockets formed at either side of each pedestal jaw are defined by walls cast integrally with the frame and a top wall in each case affords a seat for a spring group so that the weight of the frame on the supported bolster and car body is supported at said seats.

In my novel side frame structure the diagonal portion of each tension member merges at an intermediate point with the inner corner of the inner spring pocket at each end of the frame and a diagonal strut is connected between the compression member and the tension member at said point of mergence, thus greatly adding to the strength of the side frame structure. My novel side frame comprehends such an arrangement of parts as will efficiently meet the various requirements of present day foundry practice and pass the present standard A. A. R. test requirements.

Figure 1 is a top plan view of a railway car truck embodying my invention, only one-half of the truck structure being shown inasmuch as the structure is similar at opposite sides thereof, the figure being partly in section through the pedestal jaws with the journal box and asso-

ciated parts in elevation, the section being indicated by the line 1—1 of Figure 2.

Figure 2 is a side elevation, half in section, of the truck structure shown in Figure 1, the section being substantially taken in the longitudinal vertical plane bisecting the side frame as indicated by the line 2—2 of Figure 1.

Figure 3 is a sectional view substantially in the transverse vertical plane bisecting the truck as indicated by the line 3—3 of Figure 1.

Figure 4 is a sectional view in the vertical transverse plane defined by the axis of the wheel and axle assembly at one end of the truck, said section being taken substantially as indicated by the line 4—4 of Figure 2.

Figures 5, 6 and 7 show an alternate form of connection between the bolster and side frame, Figure 5 being a fragmentary side elevation, Figure 6 a sectional view substantially in the plane indicated by the line 6—6 of Figure 5, and Figure 7 a fragmentary top plan view.

Figure 8 is a fragmentary sectional view taken substantially in the vertical longitudinal plane indicated by the line 8—8 of Figure 1.

Figure 9 is a view in elevation of the side frame, only one end being shown inasmuch as the structure is similar at opposite ends.

Figure 10 is a top plan view of the side frame structure shown in Figure 9 and Figure 11 is a bottom plan view thereof.

Figure 12 is a sectional view through the side frame structure shown in Figure 9, taken substantially in the transverse vertical plane bisecting it and as indicated by the line 12—12 of Figure 9.

Figure 13 is a sectional view through the side frame in the transverse vertical plane indicated by the line 13—13 of Figure 9.

Figure 14 is an end elevation of the side frame structure.

Figure 15 is a fragmentary sectional view through a portion of the side frame structure taken substantially in the transverse planes indicated by the line 15—15 of Figure 9.

Figure 16 is a sectional view through the compression member of the side frame as indicated by the line 16—16 of Figure 9.

Figure 17 is a section through one column, taken substantially in the horizontal plane indicated by the line 17—17 of Figure 12.

Figures 18, 19 and 20 show the manner of applying wear plates to my novel side frame structure, Figure 18 being a side elevation, Figure 19 a sectional view substantially in the plane indicated by the line 19—19 of Figure 18, and Figure

20 a horizontal sectional view through the pedestal guides substantially in the plane indicated by the line 20—20 of Figure 18.

Figures 21 and 22 show an alternate form of connection between the side frame and bolster, Figure 21 being a side elevation of the arrangement, and Figure 22 a sectional view therethrough substantially in the planes indicated by the line 22—22 of Figure 21.

Describing my novel structure in greater detail, it comprises the side frame 2 of modified truss type comprising the compression member 4 and the tension member 6 with the spaced integral columns 8, 8 forming a bolster opening 10 within which is received the widened end portion 12 of the bolster 14, said bolster having the usual center bearing 16 and the side bearing 18. The bolster end is seated directly as at 20 (Figure 3) on the top chord 22 of the tension member beneath said bolster opening, said bolster having the downwardly directed inboard flange or jaw 24 and outboard flange or jaw 26 cored away as at 28, 28 and finished on their opposite faces to afford close fit as at 30, 30 with abutting surfaces on the inboard and outboard faces of said tension member. If desired the bolster may be afforded some degree of rocking longitudinally of the side frame on the seat 20 by providing a slightly arcuate surface on the bottom wall of said bolster as best seen at 31 in the section through said seat (Figure 2).

In the alternate method of connection between the side frame and bolster as shown in Figures 5, 6 and 7, the bolster 9 is afforded a jaw end having inboard vertical flanges 11, 11 and outboard vertical flanges 13, 13 relieved at their bases as at 15, 15 and machined on their opposite faces to afford a close fit as at 17, 17 with the abutting machined faces on the inboard and outboard edges of the guide portion 19 of the adjacent column 21. The bolster end is seated as at 23 upon the tension member of the side frame and may be afforded clearance as at 27 to permit longitudinal rocking of the side frame as in the before-mentioned modification. Except for the modification of the columns, the structure of the side frame is similar to that of the previous modification.

The said tension member beneath said bolster opening 10 is of box section having the bottom wall 32 and the inboard and outboard walls 34 and 36. The top chord 22 of the tension member extends diagonally upward at either side of the bolster opening and continues as at 38 through the box section 39 over the journal box and into the wall 40 defining the outer pedestal jaw. The compression member over the bolster opening 10 is of box section at the center (Figure 12), the bottom chord thereof being cored out as at 45 (Figure 2) and merging as at 41 with the column 8 and outwardly of the column said compression member has an inverted U section (Figure 16) with inturned flanges reflanged as at 43, said inverted U section merging with the before-mentioned box section 39 over the journal box. The tension and compression members of the side frame thus merge in the end portions thereof to form pedestal jaws as a means of connection to the journal boxes 42, 42 at opposite ends of the frame and associated with said boxes in the usual manner are the spaced wheel and axle assemblies 44, 44. The bottom chord 32 of the tension member as well as the inboard and outboard walls 34 and 36 thereof are continuous toward the opposite ends of the frame with the

horizontal strut 46, said bottom web 32 being cored away as at 33 (Figure 11) so that the strut 46 comprises the outboard leg 35 and the inboard leg 37, and said strut together with the diagonal portion of the tension member and the inner wall 48 of the spring pocket define the window opening 50 below the diagonal portion of the tension member. Spaced window openings 52 and 54 are also formed above the diagonal portion of the tension member between said tension member and the compression member 4, said openings 52 and 54 being spaced by the diagonal strut 56 interposed therebetween, said strut merging with the compression member at its upper end and at its lower end with the diagonal portion of the tension member and the inner top corner of the spring pocket 62. The spring pocket 62 is formed between each wall 48 and the adjacent inner pedestal guide 58, said pocket being defined at the top thereof by the horizontal wall 60, said wall affording a seat for a spring group diagrammatically shown at 64 and the side wall of said spring pocket is cored away as at 66 to afford a view into said pocket for inspection of said spring group. A spring pocket 63 is formed at the opposite side of the journal box within the box section of the outer pedestal jaw, housing also a spring group 64, said pocket being defined by the horizontal top wall 65, the outer vertical wall 67 and inboard and outboard lateral walls 69 and 71 (Figure 11).

Each journal box 42 is mounted upon the journal end 68 of the associated wheel and axle assembly through the medium of the usual brace 35 and webs (not shown) and on the top of said box is afforded positioning means as at 70 (Figure 4) for the hanger seat 72, said seat affording a means of support for the hanger 74, the top of which extends across said box and the legs 40 of which embrace the box. The lower ends of the hanger legs are afforded aligned openings 76, 76 in which may be seated the beam 78, said beam having at its opposite ends seats as at 80, 80 for bottom spring cups 82, 82, said bottom spring cups affording seats for the opposite ends of the spring groups 64, 64 and having up and down sliding relationship with the walls of the before-mentioned spring pockets 62 and 63.

Inboard and outboard securing straps may be bolted as at 84, 84 (Figure 4) across the inboard and outboard faces of the pedestal jaws of the side frame. Each journal box 42 is afforded outboard vertical guide flanges or ears 86, 86 at opposite sides of the box as a means of confining the outboard ends of the chafing plates 88, 88 at opposite sides of the box, said chafing plates likewise being fitted as at 90, 90 in slots at the inboard end of the box. The chafing plates 88, 88 have sliding movement as at 92, 92 with wear plates afforded on the pedestal jaws of the frame as more particularly described hereafter.

On the top wall of each journal box 42 and at the inboard edge thereof is afforded a vertical lug 94 through which may be bolted as at 96 the brake carrier 98, said carrier being in the form of rectangular framework with side members 100, 100 and end members 102, 102 extending transversely of the truck, also spaced intermediate struts 103, 103, said carrier supporting as at 104 intermediate brake hanger brackets 106 with brake hangers 108 supporting brake heads 110 and brake shoes 112 for engagement with the peripheries of the adjacent wheels. The said carrier frame 98 also limits the relative lateral motion between journal boxes at opposite sides of

the truck. On the top inboard corners of each journal box are formed small spring pockets 114, 114 defined in part by the chafing plates 88, 88 (Figure 8) within which pockets may be received the resilient members diagrammatically shown at 116, said resilient members extending outwardly of said pockets to afford seats as at 118 for the carrier frame 98 on the opposite corners of the box, thus affording some resilient stability therefor. Each cross member 102 of the carrier 98 is afforded spaced loop brackets 120, 120 underlying the brake beams 122, 122 upon which are mounted the before-mentioned brake heads 110, 110. Each strut 103 of the carrier 98 affords pivotal support as at 124 for a brake lever 126, said brake levers being pivotally connected intermediate their ends as at 128 to the brake beam fulcrums and pivotally and adjustably connected at their lower ends as at 130 and 132 to opposite ends of the compression bars 134, 134 at opposite sides of the truck. Safety straps 136, 136 are supported from the beams to underlie said compression bars. The brake levers 126, 126 at one end of the truck are connected to links 138. The opposite ends of the links are pivotally connected as at 140 to the equalizer 142, the midpoint of which affords a connection as at 144 for actuating means for said brake.

The detail of the side frame structure is shown in Figures 9 to 17 inclusive. Most of the features shown therein have already been referred to in the above description. Some further mention may be made of details. The frame is of truss type with spaced jaws at each end defining the pedestal opening 145 and each pedestal is in the form of a box section in order to afford a housing for a spring group at each side of the pedestal jaw. Each column 8 is of U section over most of its length, the central web of which is cored out as at 146 and the flanges of which are re-flanged as at 148, 148 (Figure 17). The top chord of the compression member is continuous to the extremity of the side frame and has a bifurcated form over the pedestal leg at the end of the frame, the opposite legs of said bifurcated portion tapering off and merging as at 150 with the inboard and outboard side walls which with the inner wall 73 and the outer wall 67 define said pedestal leg at the extremity of the frame. The said inboard and outward side walls are cored away above the horizontal wall 65 as at 156 and below said wall as at 158, 158. The openings 158, 158 permit inspection of the spring group confined within the pedestal jaw. The inner walls 58 and 73 of both jaws are cored away as at 159, 159 (Figure 13) and the outer wall 67 of the outer jaw is cored away as at 161 (Figure 14). The inner wall of each jaw is slotted from the lower end as at 160, 160 (Figures 13 and 14), said slots being aligned to accommodate the before-mentioned beam 78 upon the opposite ends of which are supported the bottom spring seats. The said slots are reinforced by flanges 162 extending entirely there-around and the edges of said flanges afford seats for wear plates which may be welded thereto as at 164, 164 (Figure 9) as more particularly described hereafter. Along inboard vertical edges of the journal opening 145 are formed the vertical flanges 166, 166 (Figures 13 and 14) which may limit the lateral motion of the side frame with respect to the journal box. At the lower extremities of both jaws are formed the longitudinally aligned inboard and outboard pads 75

168, 168 affording seats for the before-mentioned securing straps.

The wall 60 defining the top of the spring cavity inwardly of the pedestal jaw merges at one end 5 with the vertical wall 58 of the pedestal jaw and at its opposite end as at 170 (Figure 2) with the diagonal web of the tension member and at the same point with the transverse web 172 (Figure 15) of the diagonal strut 56, said web 172 being 10 generally V-shaped with its bottom edges cored away as at 174, 174 where said web merges with the spaced walls defining the said strut 56.

Figures 18, 19 and 20 show the manner in which I apply wear plates to my novel side frame 15 at the wear surfaces on the columns and on the inner faces of the spring cavities. Each spring cavity is afforded similar wear plates 176, 176 fitted into the opposite corners of the spring pocket remote from the pedestal jaws, and likewise each pocket is afforded similar angle wear plates 178, 178 for the other two corners of the spring cavity. Also facing wear plates 180, 180, similar in form, are afforded for the pedestal jaws on opposite faces thereof and each of the 20 plates 180 is cut away at the slot 160 for the purpose already described. Each of the slots 160 is afforded a U shaped wear plate 180, also similar in form, and all of said wear plates may be welded along their abutting edges and other 25 margins as at 184, 184 as best seen from the sectional view of Figure 20.

Figures 21 and 22 show a modified form of connection between the bolster and side frame wherein the bolster end 14 is afforded openings 35 190, 190 in the bottom wall thereof to accommodate dowels 192, 192 upstanding on the top chord of the tension member below the bolster opening. Said dowels are afforded aligned openings 194, 194 in the opposite walls thereof within which 40 may be received a cotter pin, bolt or similar securing member. The said dowel connection between the side frame and bolster adds to the security of the connection therebetween, preventing accidental displacement and affording 45 additional squaring means.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a railway car truck, a truss side frame 55 comprising a compression member, a tension member, and spaced columns defining a bolster opening, a bolster having a bottom jaw fitted over the top chord of said tension member at the bottom of said opening, said top chord continuing diagonally upward toward the end of the frame to merge with said compression member and form a box-section adjacent the end of said frame, a pedestal opening beneath said box-section, box-like spring pockets formed at each 60 side of said pedestal opening with top walls defining spring seats, spring groups in said pockets, a supporting wheel and axle assembly journaled in said opening, a journal box therefor, a hanger supported on the top of said box and supporting a spring beam therebeneath, said spring beam affording support for the lower ends of said spring groups, and a diagonal strut extending between said compression member and the top inner corner of the inner spring pocket.

2. In a railway truck, a truss side frame hav-

ing tension and compression members and spaced columns forming a bolster opening, a bolster seated on the top chord of said tension member beneath said opening in rocking relationship therewith longitudinally of said truck, said tension and compression members merging with each other to form a box-section adjacent each end of said frame, a pedestal opening beneath each box-section, a spring pocket at opposite sides of each pedestal opening with top walls defining spring seats for support of said frame, spaced wheel and axle assemblies with journal boxes journaled in said openings, hangers supported on said boxes and supporting beams therebelow, and a spring group mounted on each end of each beam with an end received in the adjacent pocket for reciprocal movement therein as said spring group is compressed and released in operation of said truck, said tension member top chord extending diagonally upward from the bottom of said bolster opening to each end of the frame and being continuous with the bottom chord of the box-section over each pedestal opening, each top wall inward of the adjacent pedestal opening having its inner end merging at an intermediate point with the adjacent diagonal portion of said top chord, and diagonal struts each extending from the compression member adjacent its juncture with one of said columns to the top chord of said tension member adjacent its juncture with the top wall of the inner of said spring pockets.

3. In a railway car truck, a truss side frame having tension and compression members, and spaced columns forming a bolster opening, a bolster seated on the top chord of said tension member beneath said opening in rocking relationship therewith longitudinally of said truck, said tension and compression members merging with each other to form a box-section adjacent each end of said frame, a pedestal opening beneath each box-section, spring pockets at each side of said pedestal opening with top walls defining spring seats for support of said frame, spaced wheel and axle assemblies, journal boxes journaled in said openings, hangers supported on said journal boxes and supporting beams therebelow, and spring groups mounted on respective ends of said beams and in abutment respectively with the adjacent seats for reciprocal movement in said pockets in operation of said truck, said tension member top chord at each end of the frame extending diagonally upward from beneath said bolster opening and being continuous with the bottom chord of the box-section over the adjacent pedestal opening and extending around said pedestal opening to define a pedestal wall, each spring seat top wall inward of the adjacent pedestal opening having its inner end merging with the adjacent diagonal portion of said tension member at an intermediate point thereof, and diverging therefrom toward said last-mentioned pedestal opening, and a diagonal strut extending from the juncture of each inner spring seat top wall with the top chord of the tension member to the compression member adjacent its juncture with one of said columns.

4. In a railway car truck, a truss side frame having tension and compression members and spaced columns forming a bolster opening, a bolster seated on the top chord of said tension member beneath said opening in rocking relationship therewith, said tension and compression members merging with each other to form a box-

section adjacent each end of the said frame, a pedestal opening beneath each box-section, a spring pocket at each side of each pedestal opening with a top wall defining a spring seat, spaced wheel and axle assemblies with journal boxes journaled in said openings, hangers supported on said boxes and supporting beams therebelow, and a spring group mounted on each end of each beam with an end received in the adjacent pocket for reciprocal movement therein as said spring groups are compressed and released in operation of said truck, each of said spring pockets having a rectangular box-like form with wear plates welded therein.

5. In a four wheel railway car truck, a cast steel truss side frame having tension and compression members, and spaced columns forming therewith a central bolster opening, a bolster seated on said tension member beneath said opening and afforded rocking relationship with said frame longitudinally thereof, said bolster having a jaw end portion embracing said frame inboard and outboard thereof at the bottom of said bolster opening, said tension and compression members merging adjacent their ends with pedestal end portions defining a journal opening, said tension member having a box-section beneath said bolster opening with a top web extending diagonally upward without interruption from a corner of said bolster opening and continuing over the top of said journal opening to merge with a vertical wall defining the pedestal at the remote side of said journal opening, a horizontal wall at the near side of said journal opening defining a spring seat for support of said frame, said horizontal wall merging at its inner end with said diagonal web approximately midway said bolster opening and said journal opening, and a diagonal strut extending between said compression member and the juncture of said horizontal wall and diagonal web.

6. In a cast steel truss side frame, tension and compression members, and spaced columns forming a bolster opening, said tension member comprising a top web defining the bottom wall of said opening and extending diagonally upward from the corner of said opening to merge with said compression member adjacent the end of said frame, integral pedestal jaws defining a pedestal opening at the end of said frame, integral walls defining spring pockets at each side of said pedestal opening, each pocket comprising a horizontal top wall affording a spring seat for support of said frame, the horizontal wall of the inner spring pocket merging at its inner end with said diagonal web, a diagonal strut extending between said compression member and said horizontal wall and diagonal web adjacent their juncture, and a horizontal strut extending between the bottom of the inner spring pocket and said tension member beneath said bolster opening, said horizontal strut comprising a bottom web, and inboard and outboard flanges continuous with the bottom web and inboard and outboard walls of said tension member.

7. In a truss side frame, tension and compression members merging adjacent their ends in pedestal jaws defining a journal opening, spaced columns extending between said members and forming therewith a central bolster opening, said tension member having a top web defining the bottom of said opening and extending diagonally upward from the corner thereof to form a top wall of said journal opening and continuing over said journal opening to form a vertical wall at

the remote side thereof, integral vertical walls, a horizontal top wall defining a spring pocket at each side of said opening, said horizontal walls affording seats for support of said frame, said diagonal web merging with the adjacent horizontal wall at the upper inner corner of the adjacent spring pocket, a diagonal strut extending between said compression member and the juncture of said diagonal web with said horizontal wall, and a horizontal strut extending between a portion of said tension member beneath said bolster opening and the lower end of said last-mentioned spring pocket.

8. In a four wheel railway car truck, a cast steel truss side frame having tension and compression members, and spaced columns forming therewith a central bolster opening, a bolster seated on said tension member beneath said opening and afforded rocking relationship with said frame longitudinally thereof, said bolster having a jaw end portion embracing said frame inboard and outboard thereof at the bottom of said bolster opening, said tension and compression members merging adjacent their ends with pedestal end portions defining a journal opening, said tension member having a box-section beneath said bolster opening with a top chord extending diagonally upward without interruption from a corner of said bolster opening and continuing over the top of said journal opening to merge with a vertical wall defining the pedestal at the remote side of said journal opening, and a horizontal wall at the near side of said journal opening defining a spring seat for support of said frame, said horizontal wall merging at its inner end with said diagonal chord approximately midway said bolster opening and said journal opening.

9. In a railway car truck, a truss side frame having tension and compression members and spaced columns forming therewith a bolster opening, a bolster seated on the top chord of said tension member beneath said opening in rocking relationship therewith, said tension and compression members merging with each other to form a box-section adjacent each end of said frame, a pedestal opening beneath each box-section, spring pockets at respective sides of each pedestal opening with top walls affording spring seats, spaced wheel and axle assemblies with journal boxes journaled in said openings, hangers on said journal boxes supporting beams therebelow, and a spring group mounted on each end of each beam with one end in engagement with the adjacent top wall, said spring pockets inwardly of said pedestal openings each having a top wall merging at one extremity with the adjacent tension member approximately midway said bolster opening and said pedestal opening and otherwise spaced therefrom throughout its length.

10. In a four wheel railway car truck, a truss side frame comprising tension and compression members, and spaced columns defining a bolster opening having a widened top portion and a relatively narrow bottom portion, a bolster end receivable in said widened top portion and having jaw means for engagement with said frame at the narrow portion of said opening, said bolster having a seat on said tension member beneath said opening for rocking relationship with said frame, said tension member having a box-section beneath said opening and a top web extending diagonally upward from the corner of said opening and merging with said compression member

5 in a box-section adjacent the end of said frame, a journal opening beneath said last-mentioned box-section, said tension member web being continuous over said journal opening to merge with a vertical wall defining the pedestal at the remote side thereof, vertical lateral and end walls defining a spring pocket inward of said journal opening, said spring pocket having a top wall spaced from said diagonal web and merging therewith at one extremity intermediate the ends of said diagonal web, and a diagonal strut extending from said compression member to join said tension member at the point of mergence therewith of said top wall.

extending from a point adjacent to one of said columns between said compression member and the point of emergence of said top wall and said diagonal portion.

14. In a truss side frame, compression and tension members merging adjacent their ends to form a pedestal end portion having a journal opening, box-sections at each side of said journal opening, each comprising vertical walls and a horizontal top wall forming a spring seat for support of said frame, spaced columns forming with said members a central bolster opening, said tension member having a top chord defining the bottom wall of said opening and extending diagonally upward from the corner thereof over said pedestal opening to form a vertical wall at the remote side of said opening, said diagonal chord merging with the top inner corner of the adjacent spring pocket, a diagonal strut extending between said compression member and the juncture of said diagonal web with said pocket, and a horizontal strut extending between the lower portion of said last-mentioned pocket and said tension member beneath said bolster opening.

15. In a four wheel railway car truck, a cast steel side truss frame having tension and compression members and spaced columns forming therewith a central bolster opening, a bolster seated on said tension member beneath said opening in rocking relationship therewith, said bolster having a jaw end portion embracing said frame inboard and outboard thereof at the bottom of said bolster opening, said tension and compression members merging adjacent their ends with pedestal end portions defining journal openings, said tension member having a box-section beneath said bolster opening with a top chord extending diagonally upward from each lower corner of said bolster opening and continuing over the top of the adjacent journal opening to merge with a vertical wall defining the pedestal at the remote side of said journal opening, a horizontal wall defining a spring seat extending between each inner pedestal and an intermediate portion of said diagonal chord, a diagonal strut at each end of the frame extending from said compression member to the juncture of said diagonal chord with said horizontal wall, and a horizontal strut at each end of the frame extending between the tension member below the adjacent column and the lower inner corner of the adjacent spring pocket.

16. In a railway car truck, a truss side frame comprising a compression member, a tension member, and spaced columns defining a bolster opening, a bolster having a bottom jaw fitted over the top chord of said tension member at the bottom of said opening, said top chord continuing diagonally upward without interruption toward the end of the frame to merge with said compression member and form a box-section adjacent the end of said frame, a pedestal opening beneath said box-section, box-like spring pockets formed at each side of said pedestal opening with top walls defining spring seats, spring groups in said pockets, a supporting wheel and axle assembly journaled in said pedestal opening, a journal box therefor, a hanger supported on the top of said box and supporting a spring beam therebeneath, said spring beam affording support for the lower ends of said spring groups, the adjacent top wall merging with said diagonal chord at a middle part thereof, and a diagonal strut extending from a point adjacent one of said

columns between said compression member and said top wall and diagonal chord adjacent their juncture.

17. In a railway car truck, a truss side frame comprising a compression member, a tension member, and spaced columns defining a bolster opening, a bolster having a bottom jaw fitted over the top chord of said tension member at the bottom of said opening, said top chord continuing diagonally upward toward the end of the frame to merge with said compression member and form a box-section adjacent the end of said frame, a pedestal opening beneath said box-section, box-like spring pockets formed at each side of said pedestal opening with top walls defining spring seats, and a diagonal web connected to said compression member at a point adjacent one of said columns and to the inner corner of the inmost spring pocket, the diagonal chord of said tension member merging with said web and said wall of the inmost pocket at the juncture thereof.

18. In a cast steel truss side frame, tension and compression members, and spaced columns forming a bolster opening, said tension member comprising a top web defining the bottom wall of said opening and extending diagonally upward from the corner of said opening to merge with said compression member adjacent the end of said frame, integral pedestal jaws defining a pedestal opening at the end of said frame, integral walls defining spring pockets at each side of said pedestal opening, each pocket comprising a horizontal top wall affording a spring seat for support of said frame, the horizontal wall of the inner spring pocket merging at its inner end with a central portion of said diagonal web, and a diagonal strut extending from a point adjacent to one of said columns between said compression member and said horizontal wall and diagonal web adjacent their juncture.

19. In a truss side frame, compression and tension members merging adjacent their ends to form a pedestal end portion having a journal opening, box-sections at each side of said journal opening, each comprising vertical walls and a horizontal top wall forming a spring seat for support of said frame, spaced columns forming with said members a central bolster opening, said tension member having a top chord defining the bottom wall of said opening and extending diagonally upward from the corner thereof over said pedestal opening to form a vertical wall at the remote side of said opening, said diagonal chord merging with the top inner corner of the adjacent spring pocket, and a diagonal strut extending from a point on said compression member intermediate the emergence of said tension and compression members and one of said columns to the juncture of said diagonal chord with said pocket.

20. In a truss side frame, tension and compression members merging adjacent their ends in pedestal jaws defining a journal opening, spaced columns extending between said members and forming therewith a central bolster opening, said tension member having a top web defining the bottom of said opening and extending diagonally upward without interruption from the corner thereof to form a top wall of said journal opening and continuing over said journal opening to form a vertical wall at the remote side thereof, integral vertical walls, and a horizontal top wall defining a spring pocket at each side of said opening, said horizontal walls affording seats for

support of said frame, said diagonal web merging approximately midway said bolster opening and said journal opening with the adjacent horizontal wall at the upper inner corner of the adjacent spring pocket.

21. In a cast steel truss side frame, tension and compression members, and integral spaced columns forming a bolster opening, said tension member having a top chord defining the bottom of said opening extending diagonally upward from each corner thereof to form with said compression member a box-section adjacent each end of said frame, a pedestal opening beneath each box-section, a spring pocket formed in said frame between said pedestal jaw and said bolster opening with the top wall of said pocket defining a spring seat, said top wall merging with an intermediate part of said diagonal web, and a diagonal strut extending from a point adjacent to one of said columns between said compression member and the juncture of said wall and said diagonal web.

22. In a railway car truck, a truss side frame comprising a compression member, a tension member, and spaced columns defining a bolster opening, a bolster having a bottom jaw fitted over the top chord of said tension member at the bottom of said opening, said top chord continuing diagonally upward toward the end of the frame to merge with said compression member and form a box-section adjacent the end of said frame, a pedestal opening beneath said box-section, box-like spring pockets formed at each side of said pedestal opening with top walls defining spring seats, and a diagonal web connected to said compression member at a point adjacent one of said columns and to the inner corner of the inmost spring pocket.

23. In a truss side frame, compression and tension members merging adjacent their ends to form pedestal end portions having journal openings, box-sections at each side of each journal opening each comprising vertical walls and a top wall defining a spring pocket with a seat for support of said frame, spaced columns forming with said members a bolster opening, said tension member having a top chord defining the bottom wall of said bolster opening and extending diagonally upward from the corners thereof over each of said journal openings to form vertical walls at the remote sides of said journal openings, at opposite extremities of the frame, a diagonal strut at each end of the frame merging with the compression member adjacent the bolster opening and merging with said tension member at the juncture of the adjacent top wall with the diagonal portion of the tension member and a horizontal strut at each end of the frame extending between the tension member below the adjacent column and the lower inner corner of the adjacent spring pocket.

24. In a railway car truck, a truss side frame comprising a compression member, a tension member, and spaced columns defining a bolster opening, a bolster having a bottom jaw fitted over the top chord of said tension member at the bottom of said opening, said top chord continuing diagonally upward toward the end of the frame to merge with said compression member and form a box-section adjacent the end of said frame, a pedestal opening beneath said box-section, box-like spring pockets formed at each side of said pedestal opening with top walls defining spring seats, spring groups in said pockets, a supporting wheel and axle assembly journaled

in said opening, a journal box therefor, a hanger supported on the top of said box and supporting a spring beam therebeneath, said spring beam affording support for the lower ends of said spring groups, a diagonal strut extending between said compression member and the top inner corner of the inner spring pocket, and a horizontal strut extending between the lower inner corner of the inmost spring pocket and the tension member beneath said bolster opening.

25. In a truss side frame, compression and tension members merging adjacent their ends to form pedestal end portions having journal openings, box-sections at each side of said journal openings each comprising vertical walls and a horizontal top wall defining a spring pocket with a seat for support of said frame, spaced columns forming with said members a central bolster opening, said tension member having a diagonal chord at each end of the frame extending from said bolster opening continuously over the adjacent journal opening to merge with a vertical wall at the remote side thereof, a diagonal strut at each end of the frame connected to the compression member near the adjacent column and extending downwardly to merge with the adjacent diagonal chord at an intermediate point thereof, and a horizontal strut extending from said tension member beneath the bolster opening to the lower corner of the adjacent spring pocket.

26. In a truss side frame, compression and tension members merging adjacent their ends to form a pedestal end portion having a journal opening, box-sections at each side of said journal opening, each comprising vertical walls and a horizontal top wall forming a spring seat for support of said frame, and spaced columns forming with said members a central bolster opening, said tension member having a diagonal chord extending between the emergence of said compression and tension members and a horizontal portion of said tension member beneath said bolster opening, a diagonal strut extending from a point on said compression member adjacent one of said columns to said diagonal chord, and a horizontal strut extending between a lower part of the inner box-section at each end of the frame and the horizontal portion of said tension member.

27. In a truss side frame, compression and tension members merging adjacent their ends to form a pedestal end portion having a journal opening, box-sections at each side of said journal opening, each comprising vertical walls and a horizontal top wall forming a spring seat for support of said frame, and spaced columns forming with said members a central bolster opening, said tension member having a horizontal portion beneath said bolster opening and a diagonal portion extending between the emergence of said members and said horizontal portion, the adjacent horizontal top wall being connected to a central part of said diagonal portion, a diagonal strut extending from a point on said compression member adjacent one of said columns to said diagonal portion, and a horizontal strut extending between a lower part of the inner box section and the horizontal portion of said tension member.

28. In a truss side frame, compression and tension members merging adjacent their ends to form a pedestal end portion having a journal opening, box-sections at each side of said journal opening, each comprising vertical walls and a horizontal top wall forming a spring seat for

support of said frame, and spaced columns forming with said members a central bolster opening, said tension member having a horizontal portion beneath said bolster opening, and a diagonal portion extending upwardly between the merger of said members and said horizontal portion, a diagonal strut extending from a point on

5 said compression member adjacent one of said columns to said diagonal portion, said diagonal strut and the adjacent horizontal top wall merging with said diagonal portion of the tension member at a common point.

ROBERT B. COTTRELL.
